ALBAN CECIL WHISH, OF HAYES, ENGLAND.

MEANS FOR REGULATING THE VOLTAGE OF ELECTRICAL TRANSFORMERS.

Application filed October 15, 1928, Serial No. 312,607, and in Great Britain June 30, 1927.

This invention relates to voltage regulating means of the kind whereby the voltage of an electrical transformer, for instance an oil immersed transformer, can be regulated 5 whilst the transformer is under load, and particularly to voltage regulating means of the type in which for the purpose mentioned, sections of a transformer winding connected to successive tapping points can be cut in or 10 out of action successively, at will, by causing a pair of insulated contacts connected through switching means to an output terminal or lead, to pass over the successive stationary contacts connected to the successive tapping 15 points of the said transformer winding.

The present invention has reference to improvements in voltage regulating means of the type referred to, and it has for its chief object to provide voltage regulating 20 means of simple construction, whereby any desired number of voltage regulating steps or stages can be obtained and used for any desired time with a less number of tapping points connected to stationary tapping contacts or plates than has heretofore been the case in voltage regulating means of the type above referred to, and without the voltage regulating means itself causing any objectionable reduction of voltage or loss of 25 electric energy. It also has for its object to enable the movable contacts which co-act with the said stationary tapping contacts or plates to be operated in a simpler manner than heretofore. It also has for its object to 30 enable the current normally passing from the tapped winding to the output terminal or lead, to pass through the two movable contacts connected in parallel, so that such contacts can be made of smaller cross section than is 35 practicable in the case where the whole of the said current has normally to pass through one or other of the two movable contacts.

For this purpose, in voltage regulating means according to the present invention, 40 there is associated with the successive tapping points of a transformer winding which is connected at one end to an input terminal or lead, a control switch comprising a row of successive fixed contacts (hereinafter 45 called tapping plates) connected to the successive tapping points, and two movable contacts that are mechanically connected together, but insulated from each other, so as to form one movable device and are adapted 50 to bear simultaneously upon one only of the tapping plates but arranged at such a dis-

tance apart that when they are moved towards the next adjacent tapping plate for voltage regulating purposes, one of them can bear against the next adjacent tapping plate 60 before the other leaves the first tapping plate. The two movable contacts are respectively connected through two separate switches, to the opposite ends of an auto-transformer, or a choke coil (both hereinafter included for 65 brevity in the term auto-transformer) the middle point of which is connected to a second or output terminal for connection to an output lead. The arrangement is such that when the two movable contacts bear upon one 70 only of the tapping plates, the current flowing through the transformer winding, divides and passes in parallel through both movable contacts to the two switches and then through the two halves and middle point of the auto- 75 transformer to the output terminal. When, for reducing or increasing the voltage of the winding, the two movable contacts are simultaneously moved in one or other direction towards the next adjacent tapping plate, one 80 of the movable contacts will bear against the second tapping plate while the other movable contact still bears on the first tapping plate and current will flow through the two movable contacts and switches to the two ends of 85 the auto-transformer and thence to the middle point thereof to the output terminal. In this position of the parts, a virtual tapping point is obtained midway of the section of the winding between the two tapping points connected 90 to the two tapping plates upon which the two movable contacts are then bearing. The current then flowing through the two halves of the auto-transformer balance each other so that there is no appreciable drop of voltage 95 caused by the inclusion of the auto-transformer in circuit and no objectionable loss of energy. The movable contacts can therefore be allowed to remain in the position mentioned for any desired length of time with- 100 out disadvantage, to constitute an additional running position. Consequently, for any given number of stages of voltage regulation, the number of tapping points on the winding and the number of tapping plates, can be 105 considerably reduced as compared with voltage regulating means of the kind hereinbefore referred to. For instance, with five tapping points and five tapping plates, it is possible, by the present invention, to obtain nine 110 running positions of the voltage regulating means. In the known arrangement of the

kind hereinbefore referred to, to obtain nine running positions, it would be necessary to use nine tapping points and nine tapping plates. When it be desired to cut out or cut 5 in the section of winding included between two tapping points and tapping plates and movable contacts in the present arrangement, the two movable contacts are moved simultaneously to such an extent that both will be 10 caused to bear upon the second tapping plate, but before the rear movable contact leaves the first tapping plate during the said movement, the switch connecting it to one end of the auto-transformer is opened so that no 15 sparking can take place between the movable contact and the tapping plate when the said contact leaves the said tapping plate. This is important if the tapping plates and movable contacts be immersed in an oil tank containing 20 the transformer. By the present invention it will be seen that only one operating device is necessary for moving both of the movable contacts simultaneously, each movable contact carries only one half of the 25 current flowing from the transformer winding to the output terminal through the two switches and auto-transformer; no objectionable reduction of voltage, or loss of electric energy will be caused by the auto-transformer when the two movable contacts are 30 on one tapping plate, or when they connect two adjacent tapping plates through the two halves of the auto-transformer to the output terminal, and for any given number of running voltage regulating steps, the number of 35 tapping points and plates is considerably less than the number required in voltage regulating means of the type hereinbefore referred to.

40 The two movable contacts can be connected to the two switches through flexible connections. It is however, preferred to connect them to the two switches through two stationary contact bars that are insulated from 45 each other, are arranged parallel to the row of tapping plates, and are electrically connected to the two switches, and against which the said movable contacts are arranged to slide. The middle point of the auto-transformer may be connected direct to the outgoing 50 terminal, or it may be connected to one end of a second winding that, in effect, forms part of the winding provided with the tapping points and which is connected at its 55 other end to the said output terminal.

In the accompanying illustrative drawings, Fig. 1 shows, diagrammatically, one construction of voltage regulating means according to the invention. Fig. 2 is a similar view to 60 Fig. 1 showing a modified construction. Fig. 3 shows in side elevation and Fig. 4 in end elevation, a modified construction of control switch. Fig. 5 shows a further modified form of control switch.

65 In these drawings, A and B are the two

windings of a transformer. The winding A, say the primary winding, is connected to input and output terminals A¹ and A². The winding B, say the secondary winding, may, as shown in Fig. 1, be divided into two portions connected together in series through the aforesaid control switch, oil switches and auto-transformer, and its ends to input and output terminals B¹ and B². Or, as shown in Fig. 2, the winding B may be undivided and be connected at one end to the input terminal B¹ and at its other end portion to the output terminal B² through the said control switch, oil switches and auto-transformer direct. In each case, C, C¹, C² are tapping points on the secondary winding B connected by conductors to insulated tapping plates D, D¹, D² with which the control switch co-acts, and which are arranged in a single row.

In the example shown in Fig. 1, the control switch comprises a pair of parallel movable contact bars 1 and 2 which are rigidly connected together but insulated from each other, and a pair of stationary parallel contact bars 3 and 4 arranged at right angles to the movable contact bars. The movable contact bar 1 is arranged to bridge the stationary contact bar 3 and one or other of the tapping plates D, D¹, D² according to its position, and the movable contact bar 2 is arranged to bridge the contact bar 4 only and one or other of the said tapping plates according to its position, the two movable contact bars being adapted to bear simultaneously upon any one of the tapping plates. The said pair of movable contact bars are moved, as for instance as by a rod E, in a direction at right angles to their length for cutting in and out sections of the transformer winding B located between the tapping points C, C¹, C² and corresponding tapping plates D, D¹, D². The relative position of the movable contact bars 1 and 2 and tapping plates D, D¹, D² is such that when the bars are moving in either direction, the leading contact bar makes contact with the next tapping plate before the trailing contact bar leaves the preceding tapping plate. The stationary contact bars 3 and 4, which are also insulated from each other, are connected through oil switches, indicated at 5 and 6, to the opposite ends of an auto-transformer 7. Each oil switch 5 and 6 comprises, in the example now being described, two stationary contacts 10, 10^a and a movable contact 11. The stationary contact 10 of the oil switch at 5 is connected to contact bar 3, and the stationary contact 10^a of the switch is connected to one end of the auto-transformer 7, the stationary contact 10 of the second oil switch at 6 being connected to the contact bar 4 and the other stationary contact 10^a of the same switch being connected to the opposite end of the auto-transformer 7. The movable contact 11 of each oil switch is adapted to be actuated by suitable operating means, com-

rising for instance a rod F, to close and open a circuit between its associated pair of stationary contacts at the required times. The middle point 7^a of the auto-transformer 7 is connected by a conductor 8 to the second portion of the winding B.

When the parts in the position shown in Fig. 1, the upper portion of the winding B is connected at the tapping point C through the 10 movable and stationary contact bars 1, 2, 3, 4 and closed oil switches at 5 and 6 to the opposite ends of the auto-transformer 7 and thence from the mid-point 7^a thereof and conductor 8 to the second portion of the winding 15 B, the sections of the winding B between the tapping points C, C¹ and C² being cut out. The current then flowing in opposite directions through the two halves of the auto-transformer, balance each other's action, so 20 that there is no appreciable drop of voltage caused by the inclusion of the auto-transformer in the circuit. When it is desired to cut-in the section of the transformer winding B between the tapping points C and C¹, the 25 movable contacts 1 and 2 are moved over the contact bars 3 and 4 in the direction of the arrow and pass successively from the tapping plate D to the tapping plate D¹, the section of winding between the two plates being cut 30 into circuit when both of the movable bars bear on the tapping plate D¹. When, during this movement, the movable contact bar 2 has moved on to the contact plate D¹ and while the movable contact bar 1 is still on the contact plate D, as shown in dotted lines in Fig. 35 1, the auto-transformer 7 is connected in parallel across the section of winding B between the tapping points C and C¹, the current then passing through the conductor 8 to 40 the second portion of the winding B, being drawn half from the tapping point C and half from tapping point C¹. With the parts in the position mentioned, the midpoint 7^a of the auto-transformer becomes electrically 45 equivalent to a tapping point on the winding B midway between tapping points C and C¹. To prevent sparking between each movable contact bar 2 and 1 and the tapping plate D, when it leaves that plate, the corresponding 50 oil switch at 6 or 5 is opened before the contact bar 2 or 1 leaves the said tapping plate, so that any sparking that takes place when breaking the circuit between the tapping plate D and one or other end of the auto-transformer 7, will take place in the oil switch 55 and not in the oil tank containing the transformer, if the control switch be placed in the tank as is usually preferable. When each contact bar 2 and 1 reaches the tapping plate D¹, its corresponding switch 6 or 5 is closed. The next section of winding B can be similarly cut-in by continuing the movement of the bars 1 and 2 until they both bear on tapping plates D², the switches 6 and 5 being 65 alternately open and closed at the required

time for the purpose mentioned. By reversing the movement of the contact bars 1 and 2 and opening and closing the oil switches in the proper order and at the required times, the cut out sections of windings can again be 70 successively cut-in. In each case a virtual midway tapping point on the winding between the actual tapping points, is obtained when the movable contact bars 1 and 2 are on adjacent tapping plates. Also, the movable contact bars 1 and 2 can be left for any 75 desired time on any two adjacent tapping plates, to constitute an additional running voltage position without any objectionable reduction of voltage or loss of electrical 80 energy being caused by the auto-transformer.

Thus it will be seen that at no time during the cutting in or out of sections of the winding B, is the circuit of the winding 85 opened, so that regulation of the voltage of the transformer can be made whilst the transformer is under load. Also, it will be seen that no sparking can take place at the control switch.

The operation of the movable contacts 1 and 2 of the control switch and of the movable switch contacts 11 of the oil switches, can be effected at the required times by hand actuated means, or by motor operated actuating and controlling gear, as may be desired. 90

With the above described arrangement, there is a slight fall of voltage whilst each of the movable contact bars 1 and 2 is passing from one tapping plate D, D¹ or D² to the next one, owing to one half only of the auto-transformer winding 7 being then in action and such half acting as a reactance or choke. 100

In order to minimize the time during which the slight fall of potential can take place, the movable contact 11 in each oil switch at 5 and 6 may be adapted, on its acting to disconnect one half of the auto-transformer winding 7 from its associated stationary contact bar 3 or 4, immediately to short circuit such half of the auto-transformer winding, so that it will then serve to counteract the effect of the current then flowing through the other half of the auto-transformer winding through the other contact bar and oil switch. 110

This result can conveniently be attained, as shown in Fig. 2, by providing each of the two oil switches at 5 and 6, comprising the pair of stationary contacts 10, 10^a and the co-acting movable contact 11, as hereinbefore described, with an additional pair of stationary contacts, 12, 12^a with which the associated movable contact 11 can co-act, one of the additional contacts, namely 12, of each oil switch being connected to the said mid-point 7^a of the auto-transformer 7 and the other additional stationary contacts 12^a of the two switches being connected respectively to the opposite ends of the auto-transformer 7. The movable contact 11 of each oil 120 125 130

switch 5 and 6 is adapted to bear against one or other of its associated pairs of stationary contacts 10, 10^a or 12, 12^a. In this case, immediately either movable contact 11 is moved from its stationary contacts 10 and 10^a to disconnect one or other end of the auto-transformer winding 7 from the corresponding contact bar 3 or 4, as hereinbefore described, it is immediately caused to bear 10 against the additional pair of stationary contacts 12 and 12^a and short circuit the corresponding half of the auto-transformer winding, for the purpose mentioned. By this means drop of voltage, whilst regulating the 15 voltage of the transformer, will be limited to the moment of time that is necessary for the movable contact of each oil switch to move from one of its pair of stationary contacts to the opposite pair of stationary contacts.

20 Figs. 3 and 4 show a modified construction of control switch wherein the stationary tapping plates, C, C¹, C² are arranged in a single row above and transversely to the stationary insulated contact bars 3 and 4, and the 25 two movable contact devices are arranged to be moved longitudinally and simultaneously between the tapping plates and contact bars. In this example, one of the movable contact devices comprises upper and lower contacts 30 1^a, 1^b that are pressed apart and into contact with one or other of the tapping plates C, C¹, C² and the contact bar 3, by a spring 13, are connected together electrically by a flexible strip 14 of metal and are carried by two arms 35 15 and 16 pivoted on a pin 17 fixed to a carrier 18 of insulating material. The other movable contact device comprises upper and lower contacts 2^a and 2^b, that are pressed apart and into contact with one or other of the 40 tapping plates, C, C¹, C² and the other contact bar 4 by a spring 13^a, are connected together electrically by a flexible strip 14^a of metal and are carried by two arms 15^a and 16^a pivoted on a pin 17^a fixed to the said carrier 18. The said carrier is adapted to be moved 45 to and fro in the direction of the tapping plates and contact bars by any convenient means, as for instance, by a longitudinal screw 19, adapted to be rotated in one or other direction and at the required times but which is prevented from moving endways.

The control switch instead of being constructed with movable contact devices arranged to slide in a rectilinear direction in 50 relation to straight stationary tapping plates C, C¹, C² and contact bars 3 and 4, as hereinbefore described, may otherwise be arranged. Thus, the movable contact devices may, as shown at 1^a and 2^a in Fig. 5, be radially arranged so that they can be rotated in relation to stationary arc shaped stationary tapping plates C, C¹, C² and contact bars 3^a and 4^a in a manner that will readily be understood.

In each case it will be seen that each movable contact device is at all times in electrical

connection with one terminal, say 10, of its corresponding oil switch 5 or 6, and could if desired be directly connected to such terminal by a movable conductor and the corresponding stationary contact bar 3 or 4 dispensed with. It is however preferred to use the fixed contact bars 3 and 4.

Usually it will be preferable, as hereinbefore mentioned, to arrange the control switch within an oil filled tank containing the main transformer, but it and its associated tapping plates may be arranged outside the tank if desired. The auto-transformer may be arranged inside or outside the tank. The two oil switches will be arranged external to the tank, so as to avoid sparking therein.

The said winding B may be divided at any point of its length, as hereinbefore described with reference to Fig. 1, so that the tapping points can be arranged in any desired position on the winding. Or the tapping points may be at one end portion of the winding, as in the example shown in Fig. 2.

With voltage regulating means according to this invention, the use of duplicated tapped windings, multiple quick break switches, or separate voltage regulating apparatus, such as have heretofore been used, is avoided, and a simplified, cheaper and more efficient arrangement provided.

The present invention can be applied equally well to single phase or polyphase transformers, and whether such transformers be oil immersed or not.

The use of an auto-transformer or choke coil having a center tapping for connection to an output lead, is known in other constructions of voltage regulating means and no claim is herein broadly made for the use of an auto-transformer or choke coil in voltage regulating means.

What I claim is:

1. For regulating the voltage of an electrical transformer, the combination with a winding of the transformer connected at one end to one of a pair of terminals and having a plurality of tapping points, of a control switch comprising a plurality of stationary insulated tapping contacts connected to the respective tapping points and two movable contact devices mechanically connected together but insulated from each other and adapted to bear simultaneously on any one tapping contact, or upon two adjacent tapping contacts during movement from one tapping contact to an adjacent one, an auto-transformer the middle point of which is in electrical connection with the second terminal, two separate circuit opening and closing switches normally connecting the two movable contact devices to the opposite ends of said auto-transformer whereby each movable contact device can, during voltage regulation be disconnected from its corresponding end of the said auto-transformer before

it leaves the tapping contact upon which it is bearing and be reconnected to the auto-transformer when it reaches the next tapping contact, means for operating said circuit opening and closing switches, and each of said switches upon being operated acting to disconnect the corresponding movable contact device from one-half of the auto-transformer and immediately afterwards to short-circuit the said half of the auto-transformer.

2. For regulating the voltage of an electrical transformer, the combination with a winding of the transformer connected at one end to one of a pair of terminals and having a plurality of tapping points, of a control switch comprising a plurality of stationary insulated tapping contacts connected to the respective tapping points and two movable contact devices mechanically connected together but insulated from each other and adapted to bear simultaneously on any one tapping contact, or upon two adjacent tapping contacts during movement from one tapping contact to an adjacent one, an auto-transformer the middle point of which is in electrical connection with the second terminal, and two separate circuit opening and closing switches, normally connecting the two movable contact devices to the opposite ends of the said auto-transformer and whereby each movable contact device can, during voltage regulation, be disconnected from its corresponding end of the said auto-transformer before it leaves the tapping contact upon which it is bearing and be reconnected to the auto-transformer when it reaches the next tapping contact, each of the two circuit opening and closing switches comprising two pairs of stationary insulated contacts and a movable contact adapted to co-act alternately with each pair of said contacts, one of the contacts of one pair of contacts of one switch being connected to one of the movable contact devices of the control switch and the other contact of the pair being connected to one end of the auto-transformer, and the two contacts of one pair of contacts of the other switch being similarly connected to the other movable contact device of the control switch and to the other end of the auto-transformer, and the other two contacts of each switch being connected respectively to the mid-point and corresponding end of the auto-transformer.

Signed at London, England, this fifth day of October, 1928.

ALBAN CECIL WHISH.
